UNITED STATES PATENT OFFICE.

DANIEL E. HOFFMAN, OF PLYMOUTH, OHIO.

ADJUSTABLE SIEVE FOR SEPARATORS.

1,339,560.

Specification of Letters Patent. Patented May 11, 1920.

Application filed October 13, 1919. Serial No. 330,412.

To all whom it may concern:

Be it known that I, DANIEL E. HOFFMAN, a citizen of the United States of America, residing at Plymouth, in the county of 5 Richland and State of Ohio, have invented certain new and useful Improvements in Adjustable Sieves for Separators, of which the following is a specification.

This invention relates to improvements 10 in adjustable sieves for separators.

The present invention broadly accomplishes the same objects and results as the type of sieve shown and described in applicant's pending application filed on Oct. 22, 15 1918, Serial 259,176. It is created, constructed and designed, however, to attain the objects and accomplish the results in a more efficient, economical and effective manner.

20 The specific improvements herein shown and described that differentiate from the invention shown in the pending application heretofore identified consist in providing wind deflectors of lip formation which are 25 preferably struck from the perforated member at a predetermined angle with respect to said perforated member; said lips remaining at the same angle and position at any point of the closure of the perforations 30 by the adjustment of the closure means; to provide movable closure means for the perforations in the perforated member comprising a series of parallel slats which are connected together in spaced relation to 35 each other at their ends by angle bars; to provide a combined means of bracing the corners of the sieve frame and a bearing guide to maintain and hold the angle bars in position; to provide auxiliary braces for 40 the sieve frame that are attached to the frame to aline with the ribs formed in constructing the perforated member through the medium of a series of sections, and to provide means of clamping the auxiliary 45 braces and ribs together and in opposed relation to each other, thereby adding strength, rigidity and durability to the sieve structure.

These and other objects are attained by 50 mechanism illustrated in the accompanying drawing in which:

Figure 1 is a top plan view of the sieve showing it assembled with the perforations partially open.

55 Fig. 2 is an end view of Fig. 1.

Fig. 3 is a bottom plan view of the as-

sembled sieve showing the mesh partially open.

Fig. 4 is a section of the sieve on the line 4—4 of Fig. 3. 60

Fig. 5 is a section of the sieve taken on the line 5—5 of Fig. 3.

Fig. 6 is a fragmentary perspective view of one corner of the sieve showing the construction of the perforated member and 65 closure means upon an enlarged scale.

In the drawings reference numerals 1 and 2 represent the end frame bars of the sieve, and 3 and 4 the side bars of the frame of the sieve. 70

The perforated member comprises a plurality of sections 5, 6, and 7 which are connected together in a manner described in the pending application hereinbefore identified. 75

The drawings show a conventional construction of sieve using the three sections above identified, but it is obvious to those skilled in the art that more or less sections can be used as is found most expedient and 80 practical.

Referring now to Fig. 1 attention is called to the fact that the sections 5, 6 and 7 are fastened together leaving the ribs 8 and 9 at the points of their connection and the ends are fastened to the end bars 1 and 2 by nails 3' or other similar fastening means. The side sections which in the conventional type shown in the drawings are numbered 5 and 7 are made of such a size as to overlap a portion of the side bars 3 and 4 and they are also attached in a similar manner to the attachment of the ends of said section and are held in place and position by the cleats 10 and 11. The sections as shown 90 are provided preferably with rectangular perforations 12 which are arranged to aline with each other in series. A series of parallel slats 13 equaling in number the series of perforations are arranged to slide on the under surface of the perforated member as shown in Fig. 3. They are connected 95 together so as to be operated in unison by angle bars 14 and 15. The parallel slats are interposed between the angle bars and the bottom surface of the perforated member. The parallel slats are preferably made 100 of sheet steel which unequally bent upon itself to provide a knife-like edge 16 which projects beyond the lower edge of the other 105 bent portion of the sheet metal, so as to close up snugly against the lips 17 of the

110

perforated member. The lips are preferably struck from the perforated member at a predetermined angle of inclination with respect to the perforated member. The degree of said angle being determined by such angle that has been found by experience to be the proper degree of incidence with reference to the air blast to clean the grain or seed the most efficiently. The degree ordinarily found to be the most satisfactory is about 45°.

In order to provide corner braces to strengthen the sieve frame and at the same time provide a bearing and guiding means for the sliding movement of the angle bars 14 and 15, the braces 18, 19, 20 and 21 are provided and arranged at an angle across the corners of the sieve. The braces are arranged so as to lie in juxtaposition to 15 and to permit the angle bars 14 and 15 to move over and contact with the braces which form guide bearings to hold said angle bars in their proper place when movement is imparted to them for the purpose intended.

It will be noted that the corner braces perform two functions that is, they brace the corners of the sieve frame and also form an inclosure to retain the angle bars in position 30 that move the parallel slats in unison and they also keep the parallel slats in close contact with the bottom surface of the perforated member of the sieve.

It is well known to those who are skilled 35 in the art that sieves for separators are made in many instances of large dimensions and that they should be made and are ordinarily made of sheet metal for lightness. The effect of this construction ordinarily 40 results in sagging at the central portion of the same if some auxiliary means is not provided to prevent said sagging. In the present construction of sieve, therefore, the beads or ribs 8 and 9 are provided at the 45 connecting point of the sections which perform the function of braces on one side of the perforated member. On the opposite side a plurality of braces 22 and 23 are provided with their ends L shape to fasten to the end bars 1 and 2 as shown in Fig. 3.

The braces 22 and 23 are arranged to be fastened to the end bars 1 and 2 in alignment with, opposed to the ribs or beads 8 and 9 and located on the opposite side of the 55 perforated member.

The braces while bracing the frame at the same time provide guiding means and bearings to assist in holding the series of connected parallel slats in contact with the under-surface of the perforated member. In order to further maintain the rigidity and strength of the sieve and secure the full 60 effect of the ribs or beads 8 and 9 and the auxiliary braces 22 and 23 clamping clips 65 24 and 25 are provided to hold said braces

in close contact with each other and prevent any tendency to separate from each other during adjustment or operation.

In order to provide an efficient means for the adjustment of the series of parallel slats hereinbefore described a draw bar 26 is provided and connected to said series of parallel slats as shown in Fig. 3. Brackets 27 and 28 are fastened to the end bar 2 of the frame as shown in Fig. 3 and a rotatable 75 shaft 29 is suitably journaled in bearings formed in said brackets. A plurality of cranks 30, 31 and 32 are mounted on said rotatable shaft and securely fastened thereto by any well known fastening means either 80 by set screw, key way or the like.

Suitable apertures are provided in the angle bars 14 and 15 and in the draw bar 26 to receive the L shaped ends of the links 33, 34 and 35 and the opposite L shaped ends 85 of the links are connected through the medium of suitable apertures formed in the cranks to the cranks 30, 31 and 32 thereby connecting the series of movable slats at their ends and also to the central portion thereof 90 so as to draw said parallel slats up for adjustment purposes parallel and uniform throughout their length.

The rotatable shaft 29 has an extended portion 36 projected beyond the crank 32 95 and its end is formed rectangular at 37 to receive a wrench by means of which the shaft 29 is rotated and when rotated the parallel slats are actuated to move to and fro slidably on the bottom surface of the 100 perforated members thereby closing or opening the apertures 12 more or less to clean any size or kind of grain that the operator desires to clean.

Attention is called to the fact that the 105 perforated members are stationary and do not move during the adjustment operation of the parallel slats to close the perforations 12 more or less for cleaning the size or kind of grain desired; hence the struck-up lip 110 portions thereof forming the wind blast always remain at a constant angle and are never changed at any point of the adjustment of the movable parallel slats. This feature is important as is well known to expert threshermen, as in the ordinary type of adjustable sieve, when the size of the opening is 115 changed for adjustment purposes to clean different kinds of seed or grain the angle of the wind blast is changed making it necessary to change the wind blast to some extent after the adjustment is made. The angle of relation to the wind blast is not changed in the present invention at any point of its adjustment. It is not necessary in the present invention to change the wind blast at any point of its adjustment for efficient 120 cleaning and separation of all kinds of grain or seed. To protect the adjusting mechanism an apron 38 is provided.

The construction shown of the sieve and described has been found in practical use to be very efficient, but, however, it is obvious to those skilled in the art that immaterial changes in the construction may be made by way of subtraction or addition to the parts used without deviating from the principle of the invention; hence it is not intended to confine the present invention to the structure shown and described. The method of connecting and joining the separate sections such as 5, 6 and 7 together is not claimed or described herein as it will be the subject matter of another application.

15 I claim:

1. In a sieve for separators, a frame, a perforated member composed of a series of separate sections connected together, parallel slats slidably mounted thereunder in spaced 20 apart relation, angle bars attached to said slats, means connected to the angle bars to actuate the parallel slats in unison to close or open the perforations in the perforated member more or less as desired.

25 2. In a sieve for separators, a perforated member composed of a plurality of connected sections, a plurality of parallel slats slidably mounted to move under said perforated member and means to actuate the parallel slats.

30 3. In a sieve, a perforated member, in combination with a plurality of slats of sheet metal having one edge thereof reduced in thickness with respect to the body portion and connected to move in unison under the perforated member to vary the openings therein.

35 4. In a sieve, a perforated member, in combination with a plurality of slats of sheet metal having one edge thereof reduced in thickness with respect to the body portion, means to connect said slats to move under the perforated member in unison to vary the openings therein, and means to actuate the slats in unison.

40 5. In a sieve, a frame provided with ribs, a perforated member, a plurality of parallel slats mounted thereunder, **angle bars** attached to the parallel slats, braces secured to the frame opposed and in alinement with the ribs of the perforated member, clamping clips to clamp the ribs and braces.

45 6. In a sieve, a frame provided with ribs, a perforated member, a plurality of parallel slats mounted thereunder, angle bars attached to the parallel slats, braces secured to the frame opposed and in alinement with the ribs of the perforated member, clamping clips to clamp the ribs and braces, and means connected to the angle bars to actuate the parallel slats to slide over the perforated member in unison.

50 7. In a sieve, a frame, corner braces for said frame, a perforated member, a plurality of parallel slats slidably mounted under

said perforated member, angle irons connected to said parallel slats and so located as to slide underneath said corner braces.

8. In a sieve, a frame, corner braces for said frame, a perforated member, a plurality of parallel slats slidably mounted under said perforated member, angle irons connected to said parallel slats and so located as to slide underneath said corner braces, and means to actuate said parallel slats in unison.

9. In a sieve for separators, a frame, a member composed of a plurality of connected sections having lips struck therefrom leaving a series of openings, parallel slats 80 mounted to move under said member and means to slidably actuate the parallel slats to close the opening more or less.

10. In a sieve, a perforated member in combination with a closure means composed 85 of sheet metal slats doubled unequally thereby leaving one edge projecting beyond the other and means to connect said slats to move in unison under the perforated member to vary the openings therein. 90

11. In a sieve, a perforated member in combination with a closure means composed of sheet metal doubled upon itself unequally thereby leaving one edge projecting beyond the other and means to operate the closure 95 means, said closure means being adapted to move under the perforated member to vary the openings therein more or less as desired.

12. In a sieve comprising a meshed member composed of a plurality of connected 100 sections, a series of connected slats and means to operate said slats over the under surface of the perforated member.

13. The combination in a sieve for separators of a perforated member composed of a 105 plurality of connected sections, a frame therefor, a plurality of slats slidably mounted under the perforated member and means of connecting said slats for operation in unison. 110

14. The combination in a sieve for separators, of a perforated member composed of a plurality of connected sections, a frame therefor, a plurality of slats slidably mounted under the perforated member, 115 means of connecting said slats for operation in unison and means of imparting a sliding movement to said plurality of slats in unison.

15. The combination in a sieve for separators, of a perforated member composed of a 120 plurality of connected sections, a frame therefor, a plurality of slats slidably mounted under the perforated member, means of connecting said slats for operation in unison, means of imparting a sliding 125 movement to said plurality of slats in unison and braces secured to the frame.

16. The combination in a sieve for separators of a perforated member, a frame therefor, a plurality of slats slidably mounted 130

under the perforated member, means of connecting said slats for operation in unison, means of imparting a sliding movement to said plurality of slats in unison, braces secured to the frame and clips to clamp the braces to the perforated member.

17. A sieve comprising a member composed of a plurality of connected sections having lips struck therefrom leaving a plurality or series of openings, slats mounted under said perforated member and adapted to vary the openings in said perforated member when actuated.

18. A sieve comprising a member composed of a plurality of connected sections having lips struck therefrom leaving a plurality or series of openings, slats mounted under said perforated member and adapted to vary the openings in said perforated member and means to actuate said slats.

19. A sieve for separators comprising a meshed member composed of a series of separate parts connected together to provide channels and having lips struck therefrom leaving openings, means to close said open-

ings, braces for the perforated member and means to clamp the brace to the perforated member.

20. In a sieve, a perforated member, in combination with a series of slats having the major portion of the slats of a predetermined thickness and a minor portion adjacent and contiguous with one edge of less thickness than the major portion of the slats, said slats being connected together to move in unison to cover or uncover the perforations of the perforated member more or less.

21. In a sieve, a perforated member, in combination with a series of slats having the major portion of the slats of a predetermined thickness and a minor portion adjacent and contiguous with one edge of less thickness than the major portion of the slats, said slats being connected together to move in unison to cover or uncover the perforations of the perforated member more or less and means to impart a reciprocating movement to the slats as described and set forth.

In testimony whereof I affix my signature.
DANIEL E. HOFFMAN.
